(57) **CLAIM**

The ornamental design for a server for data, as shown and described.

DESCRIPTION

FIG. 1 is a front elevation view of a server for data showing our new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a cross sectional view thereof, in which the internal mechanism is not shown for the sake of clarity, taken along line VII-VII in FIG. 1;

FIG. 8 is a front perspective view thereof;

FIG. 9 is a rear perspective view thereof;

FIG. 10 is a front perspective view thereof, shown with environmental structure; and,

FIG. 11 is a rear perspective view thereof, shown with environmental structure.

The broken lines shown in the drawings represent portions of the server for data that form no part of the claimed design.

1 Claim, 10 Drawing Sheets
